UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A FIREPLACE-STOVE.

SPECIFICATION forming part of Design No. 22,541, dated June 13, 1893.

Application filed February 28, 1893. Serial No. 464,109. Term of patent 7 years.

To all whom it may concern:

Be it known that I, THOMAS I. RANKIN, a citizen of the United States, residing in Philadelphia, Pennsylvania, have invented a new and original Design for a Fireplace-Stove, of which the following is specification.

My design for a fire place stove is fully illustrated in the accompanying drawings, in which—

1 Figure 1 illustrates the stove in front elevation. Fig. 2 is a central sectional view.

The essential feature of my design is the double scroll ornamentation appearing upon the fire-pot section, and the blower, panels, 15 &c., as shown in the accompanying drawings.

A is the hearth, and projecting vertically from this hearth is the plate B which surrounds the fire pot section C. The band c of the fire pot section is made up of a series of 20 ribbon scrolls, and the ash pit cover D is also ornamented with the said scroll. The hood E projects over the fire pot, and is ornamented with a series of fan-like scrolls, while the door or blower F has a central handle f on which 25 is plaited ornamentation, and on each side of the handle is a single scroll coiled in the manner shown, and having short branches. In the center of each coil are cross bars.

The upper edge of the blower as well as the 30 lower edge of the hood, is straight at the center, and terminates at each side in ogee curves.

The apron G depending from the hearth is ornamented with a series of open-work scrolls intertwining, and at each corner is a ribbed 35 ornamentation.

The register section H above the hood is quadrangular in shape and is ornamented

with two scrolls extending from the base toward each other, and then separating, curving toward each end of the section, said scrolls 40 having a series of branches, which form the design as shown.

Between the hood and the register section, the plate B is suitably ornamented with a series of scrolls, and the minor features of the design are the rosettes i in each uppercorner, and the ornamentation of the panels I, each panel having a central rosette j, and above and below these rosettes on the panel are figures J made up of a series of scrolls and fan-shaped 50 ornamentation.

I claim—

1. In a design for a fire-place stove the front composed of the hood and fire-pot section as herein described and shown in the accompanying drawings.

2. In a design for a fire-place stove the hood as herein described and shown in the accompanying drawings.

3. In a design for a fire-place stove the blower as herein described and shown in the accompanying drawings.

4. In a design for a fire-place stove the apron as herein described and shown.

5. The design for a fire place stove as herein described and shown.

In testimony whereof I have signed my name to this specification in the presence of two subscribing witnesses.

THOMAS I. RANKIN.

Witnesses.

HENRY HOWSON,
JOSEPH H. KLEIN.
